UNITED STATES PATENT OFFICE.

FRANK MAGIDSON, OF IRWIN, PENNSYLVANIA, ASSIGNOR TO WESTMORELAND AUTOMATIC MACHINE COMPANY, OF IRWIN, PENNSYLVANIA, A CORPORATION OF PENNSYLVANIA.

COIN-CONTROLLED APPARATUS.

No. 918,455.

Specification of Letters Patent.

Patented April 18, 1908.

Application filed April 25, 1907. Serial No. 370,241.

To all whom it may concern:

Be it known that I, FRANK MAGIDSON, a resident of Irwin, in the county of Westmoreland and State of Pennsylvania, have 5 invented certain new and useful Improvements in Coin - Controlled Apparatus, of which the following is a specification.

This invention relates to that class of coin-controlled apparatus wherein the movement of the mechanism is controlled by an 10 electric circuit which is closed and opened by the coin or check inserted by the user of the machine.

It has been proposed heretofore, in connection with various types of coin-controlled machines, to utilize the coin for closing the circuit while the machine is in operation, with means operating automatically to release the coin at a given time or when 20 the machine has completed its operation.

One object of the present invention is to provide a coin-closed circuit which is separate and distinct from the motor circuit, and which is used only for effecting the closing 25 of the motor circuit, with means, preferably operated by the motor itself, for opening the motor circuit and stopping the machine. With the apparatus thus arranged, the heavy motor circuit is not interrupted nor 30 involved in any way in the immediate operation of the coin mechanism, thereby avoiding many difficulties and dangers of disorder incident to the placing of such mechanism in the main circuit. Furthermore, 35 a much lighter current may be utilized in the starting circuit, thus obviating the heavy arcing at the coin contacts and consequent mutilation of the coin. Also, with the present improvement, the starting circuit 40 is closed only momentarily, the coin being almost immediately released either for again closing the circuit or for passage to the coin receptacle, whereas, with the coin directly controlling the main circuit, it must 45 remain in circuit closing position all the while the machine is in operation.

A further object of the invention is to provide improved means for securing two operations of a machine for each coin inserted. A double operation may be desirable in various connections, the particular application thereof here in view being an automatic shoe polishing machine, wherein each shoe is separately polished.

In the accompanying drawings, Figure 1 55 is an interior front elevation of the improved mechanism, part of the removable front of the casing being shown. Fig. 2 is an interior side view on line 2—2 of Fig. 1, and Fig. 3 is a similar view on line 3—3 of the 60 same figure. Fig. 4 is a rear elevation of the coin-manipulating mechanism and the magnet operated thereby, and Fig. 5 is a top plan view of the same. Figs. 6 and 7 are detail views, illustrating the portion of 65 the starting circuit which is opened and closed by the removable front of the casing. Figs. 8, 9, and 10 are front elevations of the coin-manipulating mechanism, the front of the coin passage being removed. Figs. 70 11 and 12 are sectional views taken on lines 11—11 and 12—12, respectively, of Fig. 8. Fig. 13 is a detail view of the coin-controlling mechanism, the magnet, the switch in the motor circuit, and the device for 75 opening the switch, the latter being shown open in dotted lines.

The improved mechanism is here shown mounted in an upright casing provided with a removable front 3. An electric motor 4 80 is shown in the upper portion of the casing connected by belt 5 with the lowermost shaft 6 of a train of speed-reducing gearing 7, of which shaft 8 is the uppermost and slowest, being utilized for timing the operation of 85 the machine, said shaft being provided, in the present embodiment of the invention, with means for breaking the motor circuit, as will presently appear. Obviously, the train of gearing may be either extended or 90 contracted according to the speed to be imparted to the governor shaft. It is within the scope of the invention to provide a motor-actuating controlling or timing device of any suitable construction, and hence 95 the invention is not restricted to the train of gearing adaptation here shown. The train of gearing may be conveniently supported by frame 9 projecting frontwardly from the rear of casing 3. Shaft 6 is shown 100 provided with a sprocket wheel 10 to which the mechanism to be propelled may be connected by a drive chain, or the machine to be actuated may be operatively connected to the motor mechanism in any suitable 105 manner.

The motor circuit 11 may extend from any suitable source of electrical energy, and in-

terposed in this circuit is switch 12 provided with the pivoted blade 13 and the usual blade contacts 14, with a spring 15 holding the blade normally in engagement with the contacts. Pivoted between its ends to the lower extremity of blade 13 is the latch-like device 16, which is in the plane of the rotatable finger 17 secured to the insulated collar 18 on shaft 8. Finger 17 is adapted to engage the notched extremity 16' of latch 16 and move the same longitudinally and with it blade 13 from the full to the dotted line position of Fig. 13, thus breaking the motor circuit and stopping the machine, with finger 17 and latch 16 engaging and holding blade 13 out of the circuit against the pressure of spring 15, as shown in Fig. 3. The finger-engaged end of latch 16 is heavier than its opposite end, so that when the mechanism is in motion and finger 17 making its revolution, the latch-end 16' depends into the path of the finger and in position to be engaged when the finger reaches it. The mechanism thus arranged provides for stopping the motor each time shaft 8 and finger 17 make a complete revolution for automatically stopping the motor.

I will now describe the mechanism for starting the motor, this being accomplished by disengaging latch 16 from finger 17 so that the switch blade may be moved by spring 15 into circuit closing position.

19 is an ordinary bell magnet having its hammer-carrying armature 20 overhanging the end of latch 16, with a coin-controlled circuit operating to energize the magnet, whereupon the magnet armature 20 depresses the outer end of latch 16 and disengages its inner end from the holding finger 17, permitting the switch to close. Magnet 19 is included in what I term the starting circuit, which may have its source in battery 21, here shown positioned in the upper portion of casing 3. The circuit extending from the battery to the magnet is interrupted by the coin passage which I will now describe in connection with the coin manipulating parts. And the circuit is also preferably interrupted by normally open push-button switch 22 located in front 3 of the casing.

23 indicates the coin inlet or slot carried by casing-front 3 which connects with coin-chute 24, leading to the upper end of casing 25, formed of insulating material and provided with the vertical coin-passage 26. Extending from the lower end of this passage is chute 24' to the coin receptacle 27, which may be located within casing 3. Intersecting one edge of passage 26 are the vertically separated fixed contacts 28 and 29 which are connected by bar 30, and this bar is electrically connected at 31 with one pole of magnet 19. The edge of passage 26

opposite said contacts is slotted vertically, and pivoted therein between their ends are the vertically swinging coin-holding contact fingers 28' and 29' which coöperate with contacts 28 and 29 for closing the circuit through the coin 32. Above and below finger 28' are similar fingers 33 and 34, and the outer ends of all of these fingers are pivotally connected to the vertically movable bar 35, with spring 35' resisting the upward movement of the bar. One of the terminals of battery circuit 36 is connected to the upper end of bar 35, as indicated at 37, while the other terminal of said circuit is connected to the magnet, as indicated at 37'.

When bar 35 is in lowered position, fingers 28' and 29' are projected into passage 26 and operate to stop the coin either in the upper circuit-closing position, as indicated in Fig. 8, or in lower position, as in Fig. 10. When the bar is raised, said fingers are withdrawn and release the coin, as shown in Fig. 9. The intermediate finger 34 is operative only when bar 35 is raised, and its function is to hold the coin after it has been released by finger 28' until said bar can again lower so that finger 29' will be in a position to stop it, as in Fig. 10, the downward movement of the bar disengaging finger 34, as shown. The uppermost finger 33 operates to hold a coin in exactly the same way as finger 34, and is provided for preventing the machine from clogging in case two coins are inserted at once, in which event finger 33 will engage and prevent the inactive coin from so following the active coin as to interfere with the operation of the latter.

For raising bar 35, a vertically swinging arm 38 is projected therebeneath, said arm extending over shaft 8, and carried by the latter is the pin or projection 39 which turns upward beneath and raises arm 38 and lifts bar 35 for releasing the coin. Projection 39 may also operate to depress a swinging arm 40 for operating a register 41 for indicating the number of times the machine is operated. The movement of arms 38 and 40 may be resisted by spring 40.

The coin-insertion slot and push-button switch are preferably located in front 3 of the machine, and the latter is removable for giving ready access to the mechanism within. As one branch of the battery circuit 26 extends to and is interrupted by the push-button switch 22, a portion 36' of the circuit is necessarily located on the inner side of front 3, and in order that the latter may be readily removed and replaced without stopping to connect and disconnect the circuit wires, circuit 36 is connected to contact points 42 which, when front 3 is in place, bear against contacts 43 secured to casing 2, with the circuit wires connected thereto, as shown. Thus, the front of the casing may

be removed and restored without inconvenience.

When the machine is to be operated, a coin is inserted which drops into casing 25 and becomes lodged between contacts 28 and 28' as shown in Fig. 8. But the starting circuit will remain open at push-button switch 22, and until the latter is operated the magnet is not energized, and hence after the coin is inserted the push-button must be operated before the motor will start. Upon pressing the button, the starting or battery circuit is closed and the movement of magnet-armature 20 turns and releases latch 16 from holding finger 17, thus closing the motor switch, and the motor mechanism continues in operation until the switch is again opened upon the complete rotation of finger 17, as before described. The rotation of shaft 8 raises the arm 38 and with it bar 35 into the position shown in Fig. 9, thus releasing a coin from its upper circuit-closing position and permitting it to drop into engagement with the intermediate holding finger 34. As soon as the arm 38 and bar 35 lower, the coin is released from this intermediate position and drops into the lower circuit closing position, as in Fig. 10, and ready for another complete closing of the starting circuit 36, for the second operation of the machine to be accomplished by one and the same coin. The second operation of the machine raises bar 35 the second time and releases the coin from the position shown in Fig. 10 and permits it to pass to the coin receptacle.

By interrupting the starting circuit at the push button, it not only gives the operator an opportunity to start the machine at a desired instant without regard to when the coin is inserted, but also serves to place the battery circuit in operation only momentarily or while the push-button is being pressed, such momentary operation being all that is necessary for releasing the motor switch. And when the apparatus is used for obtaining two operations from the same coin, as in an automatic shoe polishing machine, the second operation does not begin, even though the coin is in circuit-closing position, until the button is pressed, thus affording the operator all the time that he may desire for removing one foot from the polishing mechanism and inserting the other foot.

I claim:—

1. The combination of mechanism to be operated, a starting circuit, means actuated by the latter when closed to start said mechanism, a coin passage interrupting the circuit and having a plurality of successively acting pairs of coin-engaging terminals, means controlling the advance of a coin from one set of terminals to another set, and a manually operated switch in said circuit.

2. In a repeating coin-operated machine, the combination of mechanism to be oper-

ated, a normally open electric circuit having a plurality of sets of coin-bridged terminals and adapted to close through any set when bridged by a coin, manually operated switch mechanism co-operating with the coin-bridged terminals to close the circuit, and means for advancing a coin from one set of terminals to another set. 70

3. In a repeating coin-operated machine, the combination of an operating electric circuit, a coin passageway, a plurality of sets of coin-bridged terminals in the passageway with said circuit connected thereto and adapted to close through any set when bridged by a coin, a manually operated switch in the circuit, and means actuated upon the full closing of the circuit for advancing the coin from one set of terminals to another set. 75

4. The combination of a motor, a coin passageway, a plurality of sets of successively operating coin-bridged terminals in the passageway, an electric circuit adapted to close through any set of said terminals when connected by a coin, means operated by the motor for releasing a coin from one set of terminals to another set, a manually operated switch in said circuit, electrically operated motor-starting means actuated when the circuit is fully closed, and motor 95 stopping means.

5. The combination of a motor, a coin passageway, a plurality of sets of successively operating coin-bridged terminals in the passageway, an electric circuit adapted to close through any set of said terminals when connected by a coin, electrically operated means actuated when the circuit is fully closed for advancing a coin from one set of terminals to another set, a normally open manually-operated switch in said circuit, electrically operated motor-starting means actuated when the circuit is fully closed, and automatically operating motor-stopping means.

6. The combination of a motor, a device for starting and stopping the motor, means actuated by the motor for operating said device to stop the motor, a starting circuit, a device in the starting circuit for operating the first mentioned device to start the motor, a coin passage interrupting the starting circuit, the latter having a succession of coin-engaging contacts in the passage, means for interrupting the movement of a coin past said contacts, and a normally open manually operated switch in the starting circuit.

7. The combination of a motor, a device for starting and stopping the motor, means actuated by the motor for operating said device to stop the motor, a starting circuit, a device in the starting circuit for operating the first mentioned device to start the motor, a coin passage interrupting the starting circuit and having a succession of coin-engaging contacts, means actuated by the motor

- for controlling the movement of a coin past said contacts, and a normally open manually operated switch in the starting circuit.
8. The combination of an electric motor and circuit therefor, a switch in the circuit, a switch-operating circuit separate and distinct from the motor circuit, a coin passage interrupting the switch-operating circuit and having a succession of coin-engaging contacts, means actuated by the motor for controlling the movement of a coin past said contacts, and a normally open manually operated switch in said switch-operating circuit.
- 15 9. The combination of an electric motor and motor circuit, a self-closing switch in the circuit, a switch opening and holding device actuated by the motor for detachably connecting with the switch-blade and opening the latter and holding it open, and coin-actuated means for breaking said detachable connection.
- 25 10. The combination of an electric motor and motor circuit, a self-closing switch in the motor circuit, a latch pivoted to the switch, a member adapted to be rotated by the motor and engage the latch for opening the switch, and coin-actuated means for disengaging the latch from said rotating member.
- 35 11. The combination of an electric motor and motor circuit, a self-closing switch in the circuit, a latch pivoted to the switch-blade, a member rotated by the motor for engaging the latch and opening the switch-blade, a starting circuit, a magnet energized by the starting circuit with the magnet armature adapted to release the latch from said rotating member, and a coin passage interrupting the starting circuit and having coin contact-terminals therein.
- 45 12. In coin controlled apparatus, the combination of an electric circuit, a coin passage interrupting the circuit, a succession of fixed contacts in one side of the passage, a corresponding succession of individually pivoted coin-holding contacts in the opposite side of the passage, said contacts being pivoted between their ends with their inner ends normally projected into coin-holding position, and an actuating member to which the outer ends of the pivoted contacts are connected.
- 55 13. In coin controlled apparatus, the combination of an electric circuit, a coin passage interrupting the circuit, a succession of fixed contact points for the circuit in one side of the passage, a corresponding succession of individually pivoted contacts in the opposite side of the passage and normally projecting in coin-holding position, a pivoted coin-holding member arranged between adjacent pivoted contacts and operating to hold a coin when released by one contact and before it engages the next contact, and an operating member to which said contacts and the intermediate member are connected.
- 60 14. In coin controlled apparatus, the combination of an electric circuit, a coin passage interrupting the circuit, a succession of fixed terminals for the circuit in one side of the passage, a corresponding succession of pivoted coin-holding contacts in the opposite side of the passage, a pivoted coin-holding member arranged intermediate the pivoted contacts, a bar to which the contacts and the said member are separately pivoted, and means for operating the bar.
- 65 15. In coin controlled apparatus, the combination of an electric circuit, a coin chute interrupting the circuit, a series of pairs of coin-connected contacts for said circuit within the passage, each pair consisting of a fixed and a pivoted contact, a pivoted coin-holding device interposed between the pairs of contacts, a second pivoted coin-holding device arranged in advance of the first pair of contacts, a bar to which all of the pivoted contacts and holding devices are connected, and means for operating the bar.
- 70 16. In coin-controlled apparatus, the combination of an electric circuit, a coin passage interrupting the circuit, a series of coin-engaging contacts at one side of the passage, a series of individually pivoted successively operating coin-holding fingers pivoted in the opposite side of the coin passage with some of said fingers opposite the first mentioned contacts and coacting therewith and the coin to close the circuit, a bar to which all of said pivoted fingers are pivoted, and means for operating the bar.
- 75 17. In coin controlled apparatus, the combination of mechanism to be operated, an electric circuit, a coin passage interrupting the circuit, a plurality of pairs of coin connected contacts operating successively to hold and release a coin, each of said pairs consisting of a fixed contact and an individually pivoted contact, and a device actuated by the mechanism to be operated for oscillating the individually pivoted contacts.
- 80 18. In coin controlled apparatus, the combination of mechanism to be operated, an electric circuit, means for operatively connecting the circuit and the mechanism to be actuated, a coin passage interrupting the circuit, a series of coin contacts in one side of the passage, a series of individually pivoted coin-holding fingers in the opposite side of the passage and coacting through the coin with the first mentioned contacts, a spring-held bar to which the pivoted fingers are connected, an oscillating arm for moving the bar in opposition to its spring, and means actuated by the mechanism to be operated for oscillating said arm.
- 85 19. In coin controlled apparatus, the com-

bination of an electric motor and motor circuit, a switch in the circuit, a speed-reducing train of gearing geared to the motor, a shaft rotated by the slow end of the train, a projection on said shaft operating to open the switch, a starting circuit, a coin passage interrupting the circuit and having coin-engaging contacts, and a device adapted

when energized by the starting circuit to close the switch.

In testimony whereof I affix my signature in presence of two witnesses.

FRANK MAGIDSON.
